Attorneys.

UNITED STATES PATENT OFFICE.

FRED E. WHITE, OF GARDNER, MASSACHUSETTS, ASSIGNOR TO CENTRAL OIL & GAS STOVE CO., OF GARDNER, MASSACHUSETTS, A CORPORATION OF MASSACHUSETTS.

GAS STOVE.

1,419,792.

Specification of Letters Patent. Patented June 13, 1922.

Application filed April 14, 1920. Serial No. 373,891.

To all whom it may concern:

Be it known that I, FRED E. WHITE, a citizen of the United States, and a resident of Gardner, in the county of Worcester and State of Massachusetts, have invented certain new and useful Improvements in Gas Stoves, of which the following is a specification.

The object of my invention is to provide a gas stove, the upper frame of which normally holds the grids, being in itself the manifold for the distribution of the gas to the burners.

Another object is to provide a cooking utensil supporting frame of a gas stove of simple and efficient construction which does not require the use of a manifold in connection therewith to supply gas to the burners.

Another object is to provide a stove in which the gas burners are uniform and of a standard size, which will allow each burner to be interchangeable with any other.

Further objects and advantages will be seen as the description proceeds, and by referring to the accompanying drawings forming a part of this specification. Throughout the drawing like numerals refer

to like parts in the various figures of which:

Figure 1 is a top plan view of one embodiment of my invention with two burners removed.

Fig. 2 is a transverse sectional view along the line 2—2 of Fig. 1.

Fig. 3 is a view partly in section and partly in elevation along the line 3—3 of Fig. 1.

The frame of a gas stove normally carrying the utensil supporting grids is shown at 1 in which is formed a channel 2 supplying the gas to valves 6. Said valves are operated by means of handles 8 in the usual manner.

Burners 3 are held in place at their rear end by supports 4 formed integral with frame 1, and at their front end, by nipple 5, forming a part of valve 6, which is at-

tached to mixing chamber 12 on the burner, in proximity to the adjustable air port 13.

The gas supplied to the rear burners is controlled by an extension spindle 7 attached to the valve handle 8 and valve proper 6. Bent elbows 14 connect the valves and mixing chambers of these burners.

In operation, the hollow frame preferably made in one piece is attached to the gas main as at 11, and by opening the appropriate valve combustible material is conveyed to the burners where it is mixed with air in the usual manner.

The advantages of this improved form of gas stove will be readily apparent as it will be seen that each burner is supplied with gas in close proximity to its burning surface which insures a proper mixture of air at all times due to the fact that each burner is supplied with gas at a uniform pressure. Heretofore, the rear burners have had an elongated mixing chamber which resulted in excessive friction of the gas causing poor combustion and a diminished pressure.

Another advantage is that I am able to do away with the highly expensive and ornamental manifold pipe usually in front of the frame which is a source of annoyance to the housewife, as this must be kept clean. Other advantages will be readily apparent to those skilled in the art as it will be seen that by the elimination of parts, and the standardization of burners, together with the fact that an equal pressure will be maintained in each burner resulting in more efficient and complete combustion, applicant has produced a device highly useful and efficient in the various arts in which a device of this character might be used. Obviously, other modifications might be devised other than that shown, but what I claim and desire to secure by Letters Patent is:

1. In combination with a stove, a frame having a channel enclosed therein, said frame having a central connecting portion

also supplied with an enclosed channel, and burners supported between the outer and central portions of the frame.

2. In combination with a stove, a frame having a channel enclosed therein, said frame having a central connecting portion also supplied with an enclosed channel, a burner opening on each side of the central connecting portion, interchangeable burn-

ers under said openings, a burner between the central portion and the outer frame, being provided with a valve connecting the central channel with said burner to supply gas thereto.

In testimony whereof, I affix my signature.

FRED E. WHITE.
